UNITED STATES PATENT OFFICE.

ROBERT V. MORSE, OF ITHACA, NEW YORK.

AIR-PUMPING APPARATUS.

1,134,215.

Specification of Letters Patent.

Patented Apr. 6, 1915.

Application filed July 5, 1911, Serial No. 897,009. Renewed September 1, 1914. Serial No. 859,717.

To all whom it may concern:

Be it known that I, ROBERT V. MORSE, a citizen of the United States, residing at Ithaca, in the county of Tompkins and State of New York, have invented new and useful Improvements in Air-Pumping Apparatus, of which the following is a specification.

This invention relates to air-compressing apparatus of the type in which a pump is employed for circulating water or other liquid, and air is drawn in and circulated with the liquid. The air may then be allowed to separate from the water or other liquid, and be stored in a tank, or in the case of a vacuum pump, may be allowed to escape with the discharge freely to the atmosphere.

One object of my invention is to increase the efficiency of pumping apparatus of this type, both for compression and vacuum purposes by introducing the air into the liquid at the suction or intake of the pump and passing both the water and the air through said pump. The water absorbs the heat of compression thus giving practical isothermal compression with its consequent advantages.

Another feature of my improvement relates to the saving of power by utilizing the discharge of the water or other liquid from the separator or storage tank for assisting in driving the circulating pump.

Another object of my invention is to provide an improved combined apparatus having the double function of draining mines or other places of water, and at the same time furnish compressed air for operating mining tools, such as pneumatic drills, or for other purposes.

In the accompanying drawings: Figure 1 is a diagrammatic sectional view illustrating my improvement applied for compressing air; Fig. 2, a similar sectional diagram showing one form of vacuum pumping apparatus embodying my improvement; Fig. 3, a sectional view illustrating one form of air intake for the pump suction; Fig. 4, a similar view, showing a modification; and Fig. 5, a view illustrating my improvement applied in connection with apparatus for draining mines.

In the practice of my invention, any suitable form of liquid circulating pump may be employed, such as the rotary or centrifugal pump, 5, as shown in Fig. 1, having a suction pipe, 6, communicating with a reservoir, 7, or other source of water supply, the

pump being driven from any suitable source of power such as the motor, 8.

According to one of the features of my improvement, the air is introduced or drawn in to the suction pipe of the pump, or at any point where the pressure is less than atmospheric, and any desired amount of air may be admitted by any suitable means, one such device being shown in Fig. 3, in which the suction pipe is contracted at the pump intake and the air inlet nozzle, 9, leads into the central portion of said intake. The air intake pipe, 18, may be provided with a throttle valve, 10, and an automatic check valve, 11, which does not open until the suction is sufficient to have filled the pump with water. A check valve, 12, may be located at the foot of the water uptake or suction pipe, 6. As the water is drawn into the pump through the restricted suction opening around the air inlet nozzle, the increased velocity of the water serves to draw in the air in the form of a continuous stream of bubbles, which are pocketed by the water and with it forced through the pump where the air is compressed and discharged with the water through the outlet pipe, 13, into a separating and storage tank, 14. Any suitable means may be employed for separating the compressed air from the water discharged from the pump.

According to the modification shown in Fig. 4, the air inlet pipe, 18, may communicate with a chamber, 15, surrounding the water suction pipe 6, and having a series of holes, 16, through which the air is admitted in the form of bubbles into the water as the same is drawn into and forced through the pump. As the mixture of compressed air and water is discharged through pipe, 13, into tank, 14, the bubbles rise and the air is separated from the water and stored under pressure in the top of the tank from whence it may be drawn off for use by a valve in any manner desired.

The water in the tank is normally maintained at a constant level by any suitable means and the return water which discharges through pipe 19, under the pressure of the tank is preferably utilized upon an impulse wheel, 17, or other motor or turbine to assist in the driving of the centrifugal pump, as shown in Fig. 1, thereby regaining a large percentage of its energy which would otherwise be lost. The velocity of the water at no time need be excessively high,

as a multi-stage pump, as shown in Fig. 5, may be used where higher pressures are desired, as will be readily understood. When the pump stops, the valve, 12, closes and retains the intake pipe, 6, full of water. Upon starting the pump, the air inlet pipe may be closed by means of valve, 10, which may then be slightly opened to permit the admission of the desired amount of air without interrupting the water suction of the pump. The check valve, 11, in the air inlet pipe may also be so loaded as to remain closed until the suction is sufficient to have filled the pump and intake pipe with water. It also serves to throttle the admission of air to some extent and closes automatically whenever the suction is broken or the pump stops.

As shown in Fig. 2, the improvement is applied as a vacuum pump for exhausting air from a chamber communicating with the air pipe, 18, and the discharge pipe, 13, from the pump may lead directly to the atmosphere, or return to the reservoir and the air allowed to escape, as indicated. In this case, it will be apparent that the height of the water column in the intake pipe, 6, indicates the measure of the degree of vacuum maintained in the air intake pipe and chamber.

As illustrated in Fig. 5, my improvement is applied in connection with a multi-stage centrifugal or turbine pump, 5*, used for draining mines, or other places, of water. In this case, the pump and motor are preferably located near the bottom of the shaft, while the separating tank, 14, may be situated at any convenient position, and the discharge pipe, 20, from the tank, leads to the top of the shaft for carrying off the drainage water. Air is introduced by inlet pipe, 18, into the suction intake, 6, of the pump, and is forced through the same with the water which is then delivered through pipe, 13, into the separating tank, 14, where the compressed air may be stored ready for use.

Where, as is the case in many mines, great quantities of water must be pumped out continuously, there will be sufficient water available, and the return pipe, 19, and impulse wheel, 17, may then be dispensed with, if desired. The apparatus then operates as an efficient system for pumping out drainage water and at the same time compressing air for use in connection with pneumatic drills and other mining tools, as indicated at 21. The height of the column of water in the drainage discharge 20 above the separating tank determines the air pressure in the tank, and the latter may be placed at the proper elevation to give the desired result in this respect.

If there is not sufficient drainage water to handle the desired quantity of air for compression, some of the water may be returned 65 from the tank through pipe, 19, and impulse

wheel, 17, and then be used over again. The amount of water flowing out of the discharge pipe or returning to the pump may be readily regulated as desired, by means of valves in the respective pipes, 19 and 20.

In the case of deep mines, or wherever found desirable, a plurality of pumps may, of course, be arranged in stages at different levels, the lower one at each stage delivering water to the suction intake of the one at the next higher level, as will be readily understood.

Any standard form of multi-stage turbine or centrifugal pump may be employed, and if preferred, the passages through the successive stages may be so designed as to diminish in size or volume from the inlet toward the outlet, and thereby adapt the compressor to the diminishing air volume due to increasing pressure.

Having now described my invention what I claim as new and desire to secure by Letters Patent, is:

1. In a pumping apparatus, the combination with a liquid circulating pump having a suction intake and a discharge, of an air inlet communicating with said intake, a source of power for driving the pump, a separating and storage tank connected to the pump discharge, and a motor device operated by a discharge of liquid under pressure from the tank for assisting in driving the pump.

2. In a pumping apparatus, the combination with a water circulating pump, of an air inlet for admitting air into the water, a source of power for driving the pump, a tank for separating the air from the water, and a motor device operated by the discharge of water under pressure from the tank to assist in driving the pump.

3. In a pumping apparatus, the combination with a rotary water circulating pump having a suction intake and a discharge pipe, of an air inlet communicating with said intake, a source of power for driving the pump, a separating tank connected to the discharge pipe for storing the air, and an impulse wheel operated by the discharge of water under pressure from the tank to assist in driving the pump.

4. In an air pumping apparatus, the combination with a multi-stage centrifugal pump having a liquid suction intake, and an air inlet whereby the air will be drawn in and forced through the pump with the liquid, said air inlet being provided with a throttle valve and a check valve, of a source of power for driving the pump, a separating tank for storing the compressed air, and a wheel operated by the discharge of liquid under pressure from said tank for assisting in driving the pump.

5. In a pumping apparatus for mines, the combination with a drainage pump having a

- liquid suction intake, and an air inlet whereby the air is drawn into and forced through the pump with the liquid, of a separating tank connected to the pump outlet for storing the compressed air, and a discharge from said tank for carrying the drainage liquid to a higher level.
6. In a pumping apparatus for mines, the combination with a drainage pump having a liquid suction intake, and an air inlet whereby the air is drawn into and forced through the pump with the liquid, of a source of power for driving the pump, a separating tank connected to the pump outlet for storing the compressed air, a discharge pipe from said tank to a higher level, and means operated by a discharge of water under pressure from the tank to assist in driving the pump.
10. 7. In a pumping apparatus for mines, the combination with a drainage pump having a suction intake, of an air inlet communicat-
- ing with the intake whereby the air is drawn into and forced through the pump with the water, a separating tank connected to the pump outlet for collecting the compressed air, and a discharge pipe from said tank to the top of the shaft for carrying the drainage water out of the mine.
8. In an air compressing apparatus, the combination with a water circulating pump having a suction intake and a discharge, and an air inlet for admitting air into the water, of a source of power for driving the pump, means connected to the discharge for separating the compressed air from the water, and a motor operated by the discharge of the water under pressure to assist in driving the pump.
